UNITED STATES PATENT OFFICE.

WALLACE W. GRIEB, OF DOWNTON GROVE, ILLINOIS.

GAME APPARATUS.

Application filed April 13, 1923. Serial No. 631,943.

To all whom it may concern:

Be it known that I, WALLACE W. GRIEB, a citizen of the United States, residing at the city of Downers Grove, in the county 5 of Du Page and State of Illinois, have invented a new and useful Game Apparatus, of which the following is a specification.

My invention relates to new and useful improvements in game apparatus, and in 10 the embodiment of my invention as herein set forth, it is designed especially for use in playing the game of "Cootie".

A further object of my said invention, is to provide a dice having a penalty or set 15 back feature to increase the difficulty and uncertainty of the game.

With the foregoing, and other objects in view, which will more particularly appear in the following specification, my invention 20 consists of the design and arrangement of parts as described in the accompanying specification, and as illustrated in the accompanying drawings, in which like numerals of reference indicate the same part throughout 25 the various views, and in which,

Figure 1 is a side elevation of a dice having my invention embodied therein.

Figure 2 is a developed surface of the six sides of a dice showing my design upon 30 each of the six sides.

Figure 3 is a developed view showing the second dice having the two faces, employed as forfeit or set back as explained herein-after.

In making my said invention, I have preferably employed dice having six sides, as shown, and having the indication upon each side, as "H" for the head, "B" for the body, "L" for the legs, "F" for the feeler, 35 "E" for the eye, and "T" for the tail upon each of one of the dice, while the other dice preferably has the indications as shown, "F" for feeler, "E" for the eye, two sides marked with "L" for legs, and two sides 40 marked with "F" for the body, as the representation of a "head" on the side marked with the "H", the representation of a leg on the side represented by "L" the representation of an "eye" on the side marked with the 45 "E" that representation of the body on the side marked with the "B" and the representation 50 of the "tail" on the side marked with the "T".

In playing the game of "Cootie" with the dice, as explained above, it is usual to use 60 two dice, one of each kind shown in the illustrations, both being thrown by the player at the same time. As is usual, the side which comes uppermost is the only side to be counted in favor of the player, and to make progress, it is necessary that certain sides shall 65 be played first, as it is necessary to secure a "body" before it is possible to attach the legs or other parts to it. The players therefore throw the dice, until each one secures one 70 having the representation of a body thereon, and then the game proceeds by adding to the body the other parts as they are represented in the play, until one or the other completes his "Cootie", by securing all 75 of the parts first, in which event he has won the game.

In the dice preferably employed by me the dice represented in Figure 2 is preferably 80 dark color, as blue or black, and the dice represented in Figure 3 is red, or some other lighter color. While I prefer to play the game with only two dice to each player, it is apparent that more dice may be employed 85 without departing from the spirit of my said invention.

While I have shown my dice as having six sides, as is usual with dice, it will be apparent 90 that the number of sides may be increased to eight, or more, without in any manner departing from the spirit of my said invention, or said dice may be made in the form of the six or more sided tops frequently employed in place of dice, without departing from the spirit of my said invention. While I have 95 shown my game apparatus as designed to play "Cootie", it is apparent that it may equally as well be employed to make other figures in the same similar character, if desired. While I have shown a monkey face, 100 as the hazard, or "set back" feature, it is apparent that said design may be of any other character as well, and may be employed to indicate a favor, if so desired by the players.

While there may be many variations of the 105 said game as played, I prefer to play said game with each "Cootie" represented by 11 parts, as body, head, two eyes, two feelers, four legs and a tail. To start scoring, the player must throw a body. If he is successful, he is entitled to another throw, and the other parts are added to the body, as thrown, 110

until the cootie is completed. Whenever the player fails to throw the dice to indicate a part which he can employ in building up his cootie, the turn passes to the next player in 5 turn. The progress of the game may be indicated by sketching the parts secured upon paper, until the cootie is completed, or it may be represented by additional dice to represent each part as won. If any player throws a 10 dice with the monkey face, the player loses his turn, and is "set back" and compelled to start anew. If preferred, the penalty may be merely loss of the amount which would have been gained on the other dice thrown, in 15 the wish of the players.

Having thus described my said invention, what I claim, and desire to secure by Letters Patent, is the following:—

1. A game apparatus consisting of two 20 dice, one having a different part of an animal on each side and the other having some of its sides provided with parts of an animal with some of its sides having a special design to indicate a forfeit.
2. A game apparatus consisting of two 25 dice, one having six sides representing six different parts of an animal to be constructed, and the second die having four sides repre-

senting four parts of the animal to be constructed in the play, and two sides, having a 30 special design to indicate a forfeit, substantially as shown and described.

3. A game apparatus consisting of two dice, one having a different part of an object 35 on each side and the other having some of its sides provided with parts of the object to be constructed with one of the sides of said other die having a special design to indicate a variance in play.

4. A game apparatus consisting of two 40 dice, one having upon each side a sectional part of an object to be constructed and the other die having on some sides sectional parts 45 of the object to be constructed and on other sides having characters indicative of a change in play.

5. A game apparatus consisting of a plurality of members having sides, each member having on its sides characters indicative 50 of an object to be constructed, one of the members having a special design on one side indicative of a change in play.

In testimony whereof, I have duly signed the foregoing specification.

WALLACE W. GRIEB.
